(57) CLAIM

The ornamental design for a canvas shoe with toe cover and two decorative foxing stripes along the toe cover, as shown and described.

DESCRIPTION

FIG. 1 is a right side perspective view of a first embodiment of a canvas shoe with toe cover and two decorative foxing stripes along the toe cover showing our new design;

FIG. 2 is a top plan view thereof;

FIG. 3 is a right side view thereof;

FIG. 4 is a bottom plan view thereof;

FIG. 5 is a left side view thereof;

FIG. 6 is a rear elevation view thereof;

FIG. 7 is a right side perspective view of a second embodiment of a canvas shoe with toe cover and two decorative foxing stripes along the toe cover showing our new design;

FIG. 8 is a top plan view thereof;

FIG. 9 is a right side view thereof;

FIG. 10 is a bottom plan view thereof;

FIG. 11 is a left side view thereof; and,

FIG. 12 is a rear elevation view thereof.

The broken lines shown on the shoe represent thread stitching.

All surfaces not shown form no part of the claimed design.

1 Claim, 6 Drawing Sheets
